237,005

GOLF BALL WASHER OR THE LIKE

Fred A. Akel, 13301 Beach Blvd.,
Jacksonville, Fla. 32216

Filed Jan. 24, 1974, Ser. No. 436,060

Term of patent 14 years

Int. Cl. D15—05

U.S. Cl. D49—11

FIG. 1

FIG. 2

FIG. 7

FIG. 3

FIG. 4

FIG. 5

FIG. 6

FIG. 1 is a top plan view of the golf ball washer showing my new design;

FIG. 2 is a front elevational view thereof;

FIG. 3 is a left end elevational view with the drum located in the washing position;

FIG. 4 is a right end elevational view with the drum in a loading and unloading position;

FIG. 5 is an elevational view substantially identical to FIG. 4 and with the door open for loading and unloading;

FIG. 6 is a bottom view thereof; and

FIG. 7 is a sectional view, on an enlarged scale, taken along line 7—7 of FIG. 1.

I claim:

The ornamental design for a golf ball washer or the like, substantially as shown and described.
